UNITED STATES PATENT OFFICE.

JOHN S. WARREN, OF FISHKILL - ON - THE - HUDSON, NEW YORK.

IMPROVEMENT IN PAPER-PULP SCREENS AND DRESSERS.

Specification forming part of Letters Patent No. 147,717, dated February 17, 1874; application filed December 1, 1873.

To all whom it may concern:

Be it known that I, JOHN S. WARREN, of Fishkill - on - the - Hudson, Dutchess county, and State of New York, have invented a new and useful Improvement in Paper-Pulp Screen and Dresser, of which the following is a specification:

Figure 1 is a top view of my improved screen, the top screen-plate being removed. Fig. 2 is a detail vertical longitudinal section of the same, taken through the line *x x*, Fig. 1. Fig. 3 is a detail vertical cross-section of the same, taken through the line *y y*, Fig. 1.

The invention will first be fully described, and subsequently pointed out in the claims.

A represents the vat into which the pulp is put to be operated upon. *B* is a shaft, which passes longitudinally through the vat *A*, and revolves in bearings attached to the ends of said vat. To one of the projecting ends of the shaft *B* is attached a pulley, *C*, to which the power is applied. To the end of the shaft *B* is attached a small gear-wheel, *D*, into the teeth of which mesh the teeth of the large gear-wheel *E* attached to the outer end of the short shaft *F*, which revolves in bearings attached to the upper part of the end of the vat *A*. To the inner end of the short shaft *F* is attached a small gear-wheel, *G*, the teeth of which mesh into the teeth of the large gear-wheel *H*, which runs loosely upon the long shaft *B*, and is rigidly attached to the end of the screen *I*, so that the said screen *I* may be revolved very slowly while the shaft *B* is revolved much more rapidly.

The screen *I* may be made with four or any desired number of sides, and its sides are slotted in the manner of ordinary paper-pulp screen-plates.

One end of the screen *I* revolves loosely upon the shaft *B*, and in the center of its other end is formed a large hole, in which is inserted a short tube, *J*, which revolves in or upon a short tube, *K*, secured in a hole in the end of the vat *A*. The tubes *J K* open into a tube or spout, *L*, attached to the end of the vat *A*, and from the upper end of which the pulp is discharged. To the shaft *B* within the tubes

J K, and fitting into the inner one of said tubes, is attached a small propeller-screw, *M*, to draw the pulp from the screen *I*, and force it out through the spout *L*, enabling it to be discharged at a higher level than the point at which the pulp stands in the vat *A*. To the shaft *B*, within the screen *I*, are attached four or more oblique plates, *N*, inclined in opposite directions with respect to each other, and which are carried around by and with the shaft *B* in its revolution, so as to give the necessary pulsations to the pulp to draw it through the slits of the screen-plates forming the sides of the screen *I*.

In large machines, the plates *N* may have their outer parts curved in opposite directions, to give more pulsations to the pulp.

In the plates *N*, near their centers, are formed openings *O*, to allow the pulp to pass through as it passes toward the discharge-opening. To the angles of the screen *I* are attached plates *P*, which project toward the shaft *B*, between the plates *N*, and are designed to prevent the pulp within the screen *I* from receiving a rotary movement from the friction of the plates *N*. To the angles of the screen *I*, especially when said screen is made with more than four sides, are attached outwardly-projecting flanges *Q*, to give the proper agitation to the pulp within the vat *A*.

Having thus described my invention, I claim as new and desire to secure by Letters Patent—

1. The oblique pulsation-plates *N*, inclined in opposite directions from each other, in combination with the shaft *B* and screen *I*, rotating at different velocities, and with the vat *A*, substantially as herein shown and described.

2. The combination of the inwardly-projecting plates *P* with the screen *I* and the pulsation-plates *N*, substantially as herein shown and described.

3. The combination of the outwardly-projecting flanges *Q* with the screen *I* and vat *A*, substantially as herein shown and described.

JOHN S. WARREN.
